UNITED STATES PATENT OFFICE.

HENRY W. AVERY, OF CLEVELAND, OHIO, ASSIGNOR TO THE AVERY STAMPING COMPANY, OF SAME PLACE.

SEAT FOR HARVESTERS OR THE LIKE.

SPECIFICATION forming part of Letters Patent No. 683,634, dated October 1, 1901.

Application filed May 8, 1901. Serial No. 59,205. (No model.)

To all whom it may concern:

Be it known that I, HENRY W. AVERY, a citizen of the United States, residing at Cleveland, in the county of Cuyahoga and State of Ohio, have invented a certain new and useful Improvement in Seats for Harvesters or the Like, (Case B,) of which the following is a full, clear, and exact description, reference being had to the accompanying drawings.

10 This invention relates to pressed-steel seats such as are used on various agricultural machines, as harvesters, cultivators, hay-rakes, &c.

15 Its object is to provide a seat which while being simple in construction shall have the metal disposed where it is most needed, so that an equally strong and durable seat may be made from less material, thereby reducing the cost.

20 These seats are commonly supported centrally on a suitable spring-bar, and the tendency to break comes at the center portion adjacent to the support. To strengthen the seat at this point, it has been customary to corrugate it; but as in stamping seats of sheet metal it is impracticable to have the original sheet thicker at one point than another the whole seat has been made heavier than is necessary, so as to have the right 25 thickness for this center portion. The present invention is designed to overcome this, providing a simple, efficient, and reinforcing-plate at the center which shall so strengthen the seat at this point that the total weight of

30 the seat and the reinforcing may be less than the corrugated seat alone. I secure the reinforcing to the seat by suitably-disposed rivets, while in order to prevent the seat turning on its supporting-bar without employing 35

40 additional members I integrally depress the reinforce to form a downwardly-extending stop for the supporting-bar. This stop is preferably made by means of dents made in the upper surface of the reinforce, which 45 dents on the under side engage the bar and limit the position of the seat thereon. The invention consists of a seat so arranged and constructed.

The drawings show my improved seat.

50 Figure 1 is a bottom plan of the seat and its supporting-bar. Fig. 2 is a vertical sec-

tion thereof on the line 2 2 of Fig. 1, and Fig. 3 is a fragmentary cross-section on the line 3 3 of Fig. 1.

As shown in the drawings, the seat proper 55 is designated A. It is stamped from a single piece of sheet metal into desirable form. Its center portion a is flat, as shown. Directly beneath this center portion is a reinforcing-plate B, which is preferably circular. This 60 reinforcing-plate is made of sheet metal and has in its upper surface dents b, which thereby form integral projections on the under side of the plate. These projections, of which there are preferably four in number, are so 65 located as to engage the edges of the supporting spring or bar C. The reinforcing-plate B is held to the seat itself by suitable countersunk rivets D. The seat, with its reinforce, is held to the bar by the central bolt 70 E and nut e.

With such a construction as described the seat proper may be made of very light material and the reinforcing-plate of material of the proper thickness, according to the weight 75 and wear, whereby the total weight of the seat and reinforce by being more efficiently placed are less than that of a seat made in one piece. The rivets D are easily put in place and are unobjectionable, while the integral bosses or projections b efficiently define the position of the seat.

I claim—

1. A seat made of sheet metal and reinforced by a plate which is riveted thereto and 85 has a downwardly-extending integral projection adapted to engage the supporting-bar, substantially as described.

2. A seat composed of sheet metal combined with a sheet-metal reinforcing-plate 90 beneath the central portion of the seat and riveted to it, said reinforcing-plate having downwardly-extended bosses formed by dents in the upper surface of the plate, whereby the position of the supporting-bar is defined, 95 substantially as described.

In testimony whereof I hereunto affix my signature in the presence of two witnesses.

HENRY W. AVERY.
